Charles Le Bleu, Los Angeles, Calif.

Application February 10, 1937, Serial No. 125,036

13 Claims. (Cl. 37—126)

This invention relates to scrapers for excavating, transporting, leveling and grading.

This invention is an improvement upon the invention disclosed in my pending application Serial No. 111,884, filed November 20, 1936, in which I disclose; a scraper having a main carrier, an auxiliary carrier, and means operably associating said carriers whereby when means are applied to the main carrier to discharge same the main carrier will act upon the auxiliary carrier, through associating mechanism, to control the discharging of the auxiliary carrier.

An object of this present invention is the provision, in a scraper having a main carrier and an auxiliary carrier, of novel means applied to the carriers to control the discharging of same successively.

Another object of this invention is the provision, in a scraper having a main carrier and an auxiliary carrier, of an independent control means for each carrier and means for actuating said controls simultaneously for controlling the discharging of said carriers successively.

Another object is the provision, in a scraper having a main carrier and an auxiliary carrier, of an independent control means applied to each carrier, and a common means for actuating said controls simultaneously to control the discharging of said carriers successively.

Still another object of this invention is the provision, in a scraper having a main carrier and an auxiliary carrier, of a control cable for each carrier and a common winding means for winding up said cables simultaneously.

Another object is the provision of a scraper including a frame including side walls, a main bottom tiltably disposed between the side walls and a scraper rigid with said main bottom for scraping up materials, said bottom and said side walls combining to form an earth carrier adapted to receive scraped up materials.

Still other objects, features and advantages of this invention will be apparent to those skilled in the art upon detailed perusal of the accompanying drawings and the following specifications wherein I exemplify and describe my invention, but it is to be understood that my invention is susceptible to modification in the combination, correlation and construction of parts, members and features, and has a wide application in the design and construction of scrapers without departing from the spirit of the invention as defined in the annexed claims.

In the drawings similar characters of reference designate corresponding parts in the several views.

In the drawings:

Figure 1 is a fragmentary plan view of my invention showing various parts in transporting position.

Figure 2 is a longitudinal section, taken on broken line 2—2 of Fig. 1, with parts in elevation.

Figure 3 is a side elevation partly in section showing the various parts in discharge position.

Figure 4 is a longitudinal section taken on line 4—4 of Figure 1, showing the various parts in loading position.

Figure 5 is a fragmentary side elevation in the discharge position facing in opposite direction to Figure 4.

Figure 6 is an enlarged fragmentary plan view partly in section showing the winding drum on the rear end of the scraper. Figure 6 faces in the direction of Figure 5.

Figure 7 is an enlarged plan view, partially in section, of the large transverse beam and associated parts disposed forwardly of the carriers.

Figure 8 is a front elevation, partly in section, of Figure 7.

Figures 9 and 10 show two views of the latch bar for securing the cable and sheave assembly against movement.

Referring now to the characters of reference on the drawings, the rigidly constructed frame is supported from the ground at its rear end by rolling supports or wheels 10 journaled one on each end of an axle 11 secured to the underside of beam 12. The frame comprises short beams 13 rigid at their rear ends with beam 12 and at their front ends with transversely extending beam 14. Beam 14 is rigidly secured at its ends to side walls 15. Side walls 15 project rearwardly above beams 13 and a shaft 16 is rigidly secured at its ends each to a side wall 15 at the upper rear ends thereof. Uprights 17 are rigid at their lower ends with beam 13 and at their upper ends with shaft 16. A pair of forwardly extending members 18 are rigidly secured each to a side wall 15 and extend from the lower rear corner of the side walls to the upper front corners thereof and thence forwardly to rigid connection each with an end of a hollow transversely extending beam 19. Beam 19 is provided with a pair of forwardly extending spaced apart members 20. Rollers 21, see Figure 2, are disposed between members 20 and suitably journaled on shafts thereon. Disposed between members 20 and in engagement at its front and rear edges with rollers 21 is an upstanding post 22, see Figure 2. Thus the front end of the frame is disposed for vertical movement on post 22. The lower end of post 22 is swivelly supported on a pony truck 23, said pony truck being provided with a draft beam 24 adapted in a conventional manner at its front end for connection to a draft device such as a tractor 25.

The front end of the main frame being supported for vertical movement on post 22, means are provided for imparting said movement as follows: members 20 are provided with a pin 26, see Figure 2, upon which is journaled sheaves 27, 60

- Figure 2. The upper end of post 22 is provided with a U-shaped extension having horizontally extending arms 28-28, carrying sheaves 29 at the rear end and a sheave 30 at its front end.
- 5 A cable 31 is secured to one of the horizontally extending arms 28-28 just forwardly of sheave 29 and extends thence back and forth about sheaves 27 and 29, thence forwardly from sheave 29 to and then downwardly about sheave 30 to 10 and about a direction change sheave 32 swivelly mounted in a conventional manner on the front ends of members 20, and thence forwardly to winding drum 33 to which it is secured, see Figure 1. Thus operation of drum 33 will actuate 15 cable 31 so as to raise and lower the main supporting frame.

Disposed between the spaced apart side walls 15 is a main carrier 34. The main carrier comprises the bottom 34' and the back wall 35 which 20 is a continuation of the bottom 34 in an upwardly and rearwardly direction to form the back wall 35. Secured to the top edge of back wall 35 is a transverse beam 36 extending across the width of the main carrier. A pair of brace bars 37 are 25 rigidly secured one to each side of the main carrier and are secured at their upper ends to cross beam 36. The front ends of brace bars 37 are pivotally mounted each to a side wall 15 as indicated at 38, Figures 2, 3, 4 and 5. The front edge 30 of bottom 34' is provided with a scraper 39 which engages the surface to be removed, which material is loaded and dumped from the apparatus. The forward edges of brace bars 37 are beveled as indicated at 40 to facilitate the passage of material into the carrier and the discharge of material therefrom. The main carrier is provided with projections 41 which are adapted to rest on beam 14, see Figure 2, and support the rear end 35 of the main carrier when the same is in lowered 40 position.

An auxiliary carrier 41 is associated with the main carrier and comprises bottom plates 42, side walls 43 and bent arms 44 all assembled as a rigid structure, the rear ends of arms 44 being pivotally 45 mounted on brackets 45 at 46, said brackets 45 being secured to the top edge of side walls 15. Thus the auxiliary carrier 41 is disposed for swinging movement in a vertical plane and adapted to be loaded in common with the main 50 carrier.

Means are provided for controlling the discharge of the main carrier 34 as follows: Cross beam 36 is provided with brackets 48 carrying a pin 49 having sheaves 50 journaled thereon. 55 The large beam 19 carries brackets 51 provided with a pin 52 having journaled thereon sheaves 53, see Figures 1 and 5. The front end of the members 20 are provided with a horizontally projecting trunnion, having journaled thereon sheave 54, see Figure 1. Shaft 16 at the rear end of the scraper, is provided with screw threads 55 which terminate at 56. Mounted for limited rotation on shaft 16 is a winding drum 57 threaded which is interiorly grooved at 58 so 60 as to receive the threads 55-56 formed on the shaft, the thread grooves 58 in the winding drum terminating adjacent one end so as to form a stop 58' as illustrated in Figure 6. In viewing Figure 5 which faces in the same direction as Figure 6, it will be seen that winding drum 57 rotates in a clockwise direction for winding up cable and in counterclockwise direction for unwinding cable. Figure 6 shows the drum 57 in wound up position with respect to the cable 65 thereon. Therefore it will be noted that wind-

ing drum 57 has limited rotational movement on shaft 16 since when the drum has been screwed onto shaft 16 to the point where the end of thread 56 contacts the stop 58' no further unwinding movement can take place. The pitch of the 5 threads on shaft 16 and in the grooves drum 57 is substantially equivalent to the pitch of the winding of cable on the drum 57. A coil spring 59 encircles shaft 16 and is secured at one end to the drum 57 at 60 and at the opposite end 10 to the stationary frame member 61 at 62. Thus the spring 59 will be compressed and wound up during the rotational movement of the drum 57, and will impart winding movement to drum 57 when said drum is free to turn in clockwise 15 direction. Viewing Figures 1, 2, 3, 5 and 6, a cable 63 is secured at one end to winding drum 57 at and after being wound thereabout passes forwardly and then back and forth about sheaves 50 and 53 and thence forwardly to and downwardly about sheave 54 and thence downwardly about direction change sheave 64, see Figure 1, swivelly mounted on the front ends of members 20 and thence forwardly to winding drum 65. Thus winding drum 65 may be operated to wind 20 up cable 63 to dispose the main carrier 34 in the discharge position of Figure 3. The function of the winding drum 57 and associated parts during the dumping operation will be described after the arrangement of the auxiliary carrier 30 has been described.

The auxiliary carrier 41 is provided at its outer end with a bracket 66 carrying a pin 67 having sheave means 68 journaled thereon. The large cross beam 19 carries brackets 69 through 35 which extends a pin 70 having journaled thereon a pair of sheaves 71. Journaled on a stop pin in the front end of members 20 is a sheave 72. A pin 73 extending through cross beam 19, and carries a pin 73, see Figure 7, having journaled thereon a plurality of sheaves 74. A movable yoke 75 is disposed within the cross pin 19 and is provided with a pin 76 having journaled thereon a plurality of sheaves 77. Yoke 75 is formed with a stem portion 78 having a stop member 79 rigid therewith. A latch bar 80 straddles the stem 78 and is adapted to engage stop member 79 and secure said yoke against movement. Latch bar 80 extends upwardly through a retainer 81 secured to cross beam 19 and is 40 pivotally connected at its upper end to an arm 82 which in turn is pivotally connected at its front end at 83 to the upper end of brackets 84 secured to cross beam 19. Thus it is seen that the rear end of arm 82 may be raised see 45 Figure 3 and 5, to withdraw latch bar 80 from engagement with stem 78 and stop 79 to permit free movement of yoke 75. It will be noted that the lower end of latch bar 80 is beveled as at 85 to facilitate re-latching action when yoke 75 50 returns to normal position. This action is further facilitated by the shape of stop member 79. Figures 9 and 10 show two views of latch bar 80.

Secured to one end of the large cross beam 65 19 are brackets 86 carrying a pin 87 having journaled thereon a sheave 88. Secured to the front wall of cross beam 19 is a tubular member 89. Arranged in tubular member 89 is a coil spring 90. Disposed in one end of coil spring 70 90 is a plug 91. Attached to plug 91 at this end is a cable 92 extending outwardly through an opening in the end of tubular member 89, then passing about sheave 88 and thence through an opening in the end of cross beam 19 to a 75

connection with yoke 75. Thus, the movement of yoke 75 toward sheaves 74 will result in compressing spring 90, and when yoke 75 is released spring 90 will return same to its normal position 5 at the end of beam 19.

A cable 93 is anchored at an end to pin 76, see Figures 7 and 8, and passes thence back and forth about sheaves 74 and 77, thence upwardly to sheave 71, thence back and forth about sheaves 10 71 and 68, thence forwardly to and downwardly about sheave 72 thence about a direction change sheave 94, and then forwardly to winding drum 65. Thus, it is seen that winding drum 65 may be operated to wind up cable 93 to control the 15 discharging of the auxiliary carrier 41.

The operation of the invention will now be described.

Note that cables 63 and 93 are both wound on winding drum 65 to control the operation of 20 same successively. The auxiliary carrier is to be discharged first, followed by the discharging of the main carrier.

Being in the loaded and transporting position indicated in Figure 2, winding drum 57 is in the 25 position indicated in Figure 6, and movable yoke 75 and related parts are in the position indicated in Figures 7 and 8, and to discharge the carriers winding drum 65 is operated to wind up cables 63 and 93 simultaneously. Since yoke 75 is 30 latched against movement toward sheaves 74 by latch bar 80 the auxiliary carrier will begin to move upwardly as soon as drum 65 begins to rotate. But this is not true regarding the main carrier even though cable 93 is also being wound 35 simultaneously with cable 63, but instead, as the auxiliary carrier 41 is moved upwardly by cable 63, cable 93 will unwind first from drum 57 before the main carrier begins to move. This unwinding of drum 57 will bring the thread end 40 56 to the end of the groove 58 and since the drum can no longer unwind the main carrier will begin to tilt forwardly about pivot 38.

At this point in the operation, the auxiliary carrier 41 will have moved upwardly to the position indicated in Figure 3. In this position of 45 the auxiliary carrier it will be noted that the rear end of arm 82, see Figure 3, has been engaged by the auxiliary carrier and raised which action frees the yoke 75 and sheaves 77 for movement toward sheaves 74 which movement will now take place as the winding drum 65 continues to wind up cables 63 and 93, and the main carrier continues to tilt forwardly. When the main carrier has reached the position indicated in Figure 3 the 50 dumping operation is completed.

From the position indicated in Figure 3 the carriers may be disposed in the relative positions indicated in Figure 4 by releasing the winding drum 65 and allowing cables 63 and 93 to unwind 55 simultaneously therefrom until the carriers have assumed the position of Figure 4 at which point the drum 65 may be stopped. The carriers will move from the position of Figure 3 to that of Figure 4 when the cables 63 and 93 are allowed to unwind from drum 65 because the wound up tension of spring 59 is not sufficient to support the main carrier in the position of Figure 4, and the expanded position of spring 90, see Figure 7, is sufficient to support the empty auxiliary carrier 60 in the open position and therefore as cables 63 and 93 are released to allow the carriers to assume the positions of Figure 4 from Figure 3, the auxiliary carrier will not begin to lower until sheave block assembly 77 has returned to the position 65 indicated in Figure 7, at which point the latch 70

bar 80 will again drop into latching association with stem 78 and stop 79 and the sheave block assembly 77 is again latched against movement toward sheaves 74. The winding drum 65 may then be stopped and the carriers retained in the 10 position of Figure 4 for loading. The auxiliary carrier 41 may be lowered from the position of Figure 4 to that of Figure 2 by simply releasing drum 65 again and allowing cables 63 and 93 to unwind. As this simultaneous unwinding of cables 63 and 93 takes place the slack that would otherwise be present in cable 93 is taken up automatically by winding drum 57 actuated by spring 59. It will be noted that the auxiliary carrier 41 may be disposed in any desired position 15 between that of Figure 2 and the position of Figure 4 without affecting the position of the main carrier as indicated in Figures 2 and 4. Two winding drums 65 could be used, one for each of cables 63 and 93 but this would require a 20 pair of control levers for the operation thereof. One of the principal advantages of my invention lies in the fact that only one control lever 95 is required to control both carriers. The other control lever 96 being used to control the raising 25 and lowering of the main frame to position the scraper 39 relative to the ground through the operation of winding drum 33 on cable 31.

No description is given of the winch mounted on the tractor for the reason that it is of conventional design, commonly referred to as "a double drum winch." The use of a single drum for simultaneously winding up two cables to control the discharging of two carriers is believed to be 30 new.

I claim:

1. In a scraper, a main carrier, an auxiliary carrier disposed forwardly of the main carrier to be loaded in common therewith, said carriers being adapted to discharge onto the ground, flexible controls for each of said carriers, common actuating means for actuating said flexible controls simultaneously to cause said carriers to operate, and means cooperating with said actuating means to cause said carriers to operate successively. 45

2. In a scraper, a main carrier, an auxiliary carrier disposed forwardly of the main carrier to be loaded in common therewith, said carriers being adapted to discharge onto the ground, a control cable applied to each of said carriers, a common winding drum for simultaneously winding up said cables so as to cause said carriers to operate and other means cooperating with said drum to cause said carriers to operate successively. 50

3. In a scraper, a frame, a main carrier pivoted to said frame, an auxiliary carrier disposed forwardly of said main carrier so as to be loaded in common therewith, said carriers being adapted to discharge onto the ground, a control cable for each of said carriers to cause the same to discharge, winding means for winding up both control cables to cause said carriers to operate, and other means cooperating with said winding means to cause said carriers to operate successively. 60

4. In a scraper, a frame, a main carrier disposed with the frame, an auxiliary carrier disposed forwardly of said main carrier to be loaded in common therewith, said carriers being adapted to discharge onto the ground, a control cable for each carrier operably associated therewith, take up means for adjusting the slack on one of said cables, a winding drum for winding up the control cables simultaneously to cause the carriers to operate, and a second means cooperating with 70

said winding drum to cause said carriers to operate successively.

5. In a scraper, a wheel supported frame, a main carrier pivoted on said frame, an auxiliary carrier pivoted to said frame and being disposed forwardly of said main carrier to be loaded in common therewith, both carriers being adapted to discharge onto the ground, a control cable for each carrier operably associated therewith, a 10 winding drum for winding up said control cables simultaneously so as to cause the carriers to operate, and means cooperating with said winding drum to cause said carriers to operate successively in predetermined order.

15 6. In a scraper, a wheel supported frame including spaced apart side walls, a main carrier having a bottom tiltably disposed between said side walls, a scraper disposed at the front edge of the main bottom, said side walls and said
20 bottom forming a receptacle adapted to receive material scraped up by the scraper, an auxiliary carrier operably pivoted to said frame forwardly of said main carrier to be loaded in common therewith, both carriers being adapted to discharge onto the ground at their confronting edges, control means associated with said carriers for discharging the same, means for taking up the slack on one of said control means, and other means cooperating with said control means for
25 causing said carriers to discharge successively in predetermined order.

30

7. In a scraper, a frame including side walls, rolling supports for the frame, a main carrier bottom tiltably disposed between the side walls, 35 a scraper disposed at the front edge of the main bottom, said side walls and the main bottom forming a receptacle adapted to receive material scraped up by the scraper, an auxiliary carrier operably disposed in front of the main carrier 40 to be loaded in common therewith, said carriers being adapted to discharge onto the ground at their confronting edges, a control cable for each of said carriers operably associated therewith, a common winding drum for winding up said control cables, and means cooperating with said drum to cause said carriers to operate successively.

5. In a scraper, a frame including side walls, rolling supports for the frame, a main carrier having a bottom tiltably disposed between the side walls, a scraper disposed at the front end of said main bottom, said side walls and said bottom forming a primary receptacle adapted to receive material scraped up by the scraper, a secondary carrier operably disposed in front of the main carrier to be loaded in common therewith, both carriers being adapted to discharge onto the ground, a control cable for each carrier operably associated therewith and a winding drum for winding up the control cables simultaneously to cause the carriers to operate, and means cooperating with said winding drum to cause said carriers to operate successively.

9. In a scraper, a frame including side walls
65 as rigid integral parts thereof, rolling supports
for the frame, a bottom wall tiltably disposed be-
tween the side walls, a scraper disposed at the
forward end of the bottom wall for scraping up
material, said side walls and said bottom con-
70 stituting a primary receptacle adapted to receive
material scraped up by said scraper, a secondary

carrier pivoted to said frame forwardly of said primary carrier to be loaded in common therewith, said carriers being adapted to discharge onto the ground at their confronting edges, a control cable for each carrier operably associated therewith and resiliently connected to said frame, a winding drum for winding up the control cables simultaneously to cause the carriers to operate, and a second means cooperating with said winding drum to cause said carriers to operate successively. 5 10

10. In a scraper, a wheel supported frame, a main carrier tiltably disposed on said frame, an auxiliary carrier pivoted to said frame and disposed forwardly of the main carrier to be loaded in common therewith, said carriers being adapted to discharge onto the ground at their confronting edges, a control cable for each carrier and having resilient means at their rear ends, a common winding drum for winding up the cables 20 simultaneously for operating said carriers, and a second means cooperating with said common winding drum to cause said carriers to operate successively. 15

11. In a scraper, a wheel supported frame, a main carrier tiltably disposed on the frame, an auxiliary carrier pivoted to said frame forwardly of the main carrier to be loaded in common therewith, said carriers being adapted to discharge onto the ground at their confronting edges, a control cable for each carrier operably associated therewith and resiliently attached at their rear ends to the frame, a winding drum for winding up the cables simultaneously for operating said carriers and a second operable means cooperating with said winding drum to cause said carriers to operate successively. 30 35

12. In a scraper, a frame including spaced apart parallel side walls as rigid integral parts thereof, a main carrier bottom tiltably disposed between the side walls, said main bottom being sidably cooperable at its ends with said parallel side walls, whereby said side walls may serve as end closures therefor, an auxiliary carrier operably disposed in front of the main carrier to be loaded in common therewith, both carriers being adapted to discharge on to the ground at their confronting edges, a control cable for each of said carriers operably associated therewith, a winding drum for winding up said cables, and means cooperating with said winding drum to cause said carriers to operate successively. 40 45 50

13. In a scraper, a supporting frame including spaced apart parallel side walls as rigid integral parts thereof, transverse beams rigidly connecting said side walls, a main carrier bottom open at both sides and pivotally supported on said side walls adjacent its forward end, said main bottom being slidably cooperable at its ends with said parallel side walls, whereby said side walls may serve as end closures therefor, an auxiliary carrier operably disposed in front of the main carrier to be loaded in common therewith, both carriers being adapted to discharge on to the ground at their confronting edges, a control cable for each of said carriers operably associated therewith, a winding drum for winding up said cables, and means cooperating with said winding drum to cause said carriers to operate successively. 55
